UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

COUNTERBALANCING DEVICE FOR OVEN DOORS.

Application filed February 16, 1925. Serial No. 9,547.

The invention has general reference to cook stoves, and more especially refers to a counterbalancing means for the oven door of a cook stove.

5 The object of the invention generally stated is to produce a counterbalancing means of simple and economical construction which is adapted effectually to support the door in its swinging movements against 10 the action of gravity, so as to facilitate its operation.

More specifically, the invention has for its 15 object the provision of a counterbalancing means which is noiseless in operation, which is compact so that it consumes little space and may be readily enclosed within the double wall structure commonly employed, and which is of a durable character, the 20 spring employed being subjected in use to very little strain.

In the accompanying drawings I have 25 illustrated a preferred embodiment of my invention, but it is contemplated that various changes in the construction and arrangement set forth may be made by those skilled in the art without departing from the spirit and scope of the invention as expressed in the appended claims.

Figure 1 of the drawings is a fragmentary 30 front elevation of the oven section of a cook stove of the gas range type, to the doors of which my invention is applicable.

Fig. 2 is a vertical sectional view taken 35 approximately in the plane of line 2—2 of Fig. 1, but on an enlarged scale.

Fig. 3 is a fragmentary vertical sectional view taken approximately in the plane of line 3—3 of Fig. 2.

Fig. 4 is a similar view taken in the plane 40 of line 4—4 of Fig. 3 and showing the relation of the parts for the open position of the door which is indicated by dotted lines.

I have herein shown my counterbalancing 45 means applied to the rectangularly shaped door 5 of the broiler oven of a gas range of which 6 designates the oven section. A similar means is applied to the door 7 of the baking oven, the lower portion of such means being shown in Fig. 2.

50 Referring more particularly to the door 5 and its counterbalancing means, this door

is suitably supported in the door frame 8 upon trunnions 9 and 10 which are integrally formed on the door. Each trunnion projects outwardly from one side edge of the door and is journaled in the door frame rearwardly of the plane of the front face of said door frame. The trunnion 9 at one edge of the door has in the present instance cast integral therewith an approximately 55 triangular member 11 providing a stop shoulder 12 which is adapted to engage with the inner side of the frame 8 as shown in Fig. 4 to limit the forward and downward 60 swinging movement of the door. 65

The triangular member 11 has pivoted thereto at 11^a eccentrically of the axis of the trunnion 9, a link 13 forming one arm of a toggle generally designated by the numeral 14 and of which the other arm is 70 formed by a link 15 pivoted at its lower end to the link 13 and at its upper end to a projection 16 on the oven frame 8. Preferably the link 15 has a bent strap 17 secured thereto at one end with its free end spaced from 75 the link 15 whereby to provide spaced aligned bearings for a bolt 18 which latter passes through the inner end of the projection 16 entered between said bearings.

The link 13 has a rearward extension 19 80 of substantial length, and the link 15 has an upward extension 20 of relatively short length. These two extensions are connected at their free ends by means of a contractile spring 21, the lower or inner end of 85 which is anchored to the extension 19 through one or the other of a row of holes 22 and the upper or outer end of which is anchored to the extension 20 by means of a forwardly opening notch or recess 23. 90

It will be observed that in the movement of the door from the vertical position, shown in Fig. 2, outwardly and downwardly to the horizontal position shown in Fig. 4, the toggle 14 is bent against the action of the spring 95 21 and that in this movement of the door the eccentric pivot 11^a of the triangular member 11 moves upwardly and inwardly through an arc of approximately 90 degrees. The spring is thus placed under tension 100 and acts to restrain the flexing of the toggle. In this operation the link 13 and its

extension 19 constitute a lever fulcrumed between its ends on the pivot connecting the link 13 with the link 15, and because the extension 19 is substantially longer than the link 13 of the toggle very little power is necessary to be exerted by the spring to restrain the flexing of the toggle sufficiently to counterbalance the door.

Conversely as the door approaches its vertical position in the closing movement of the door, the spring acts to straighten the toggle 14 but notwithstanding the fact that during the final portion of the closing movement the tension of the spring is relatively slight it is able to complete the closing movement of the door through the function of the extension 19 and link 13 as a lever. Also this final or closing movement of the door by the spring is facilitated by reason of the upward extension 20 of the link 15, forming with this link a second lever fulcrumed on the bolt 18 and receiving the application of power at its extreme upper end.

It will also be apparent that the link 15 with its extension 20 and the extension 19 of the link 13, together constitute a second toggle 24 which the spring 21 tends to flex as the first toggle 14 is straightened. Thus the link 15 forms a part of and is common to both toggles 14 and 24.

I claim as my invention:—

1. A counterbalancing device for oven doors comprising a toggle having one arm pivoted to the door eccentrically of its turning axis and the other arm pivoted to turn on a fixed axis, a contractile spring, and means including a pair of levers of which the arms of the toggle form parts operatively connected by said spring and acting to resist the flexing of the toggle and thereby restraining movement of the door from upright to horizontal position.

2. A counterbalancing means for oven doors comprising a toggle having one arm pivoted to the door eccentrically of its turning axis and its other arm mounted to turn on a fixed pivot, and means including a lever of which one of said toggle arms forms a part and a spring associated with said lever tending to straighten the toggle for all positions of the door.

3. A counterbalancing means for oven doors comprising a toggle having one arm pivoted eccentrically of the turning axis of the door and the other arm pivotally associated with the door frame, the first mentioned arm having an extension forming therewith a lever, and a spring acting upon said lever to yieldingly resist the swinging movements of said arms toward each other.

4. A counterbalancing means for oven doors comprising a toggle having one arm pivoted eccentrically of the turning axis of the door and another arm pivotally associated with the door frame, each of said arms

having an extension forming therewith a lever, and a spring connecting the extensions of said arms.

5. A counterbalancing means for oven doors or the like comprising a member rigid with the door so as to turn therewith, a toggle having one arm pivoted to said member eccentrically of the turning axis of the door, a stationary part to which the other arm of said toggle is pivoted, one of said arms having a portion extending beyond its pivotal connection with the other arm, and a spring acting upon said extending portion tending to straighten the toggle for all positions of the door.

6. A counterbalancing means for oven doors or the like comprising a member rigid with the door so as to turn therewith, a toggle having one arm pivoted to said member eccentrically of the turning axis of the door, a stationary part to which the arm of said toggle is pivoted, one of said arms having a portion extending beyond its pivotal connection with the other arm, and the other arm having a portion extending beyond its connection with the stationary support, and a spring connecting the extensions of the two arms.

7. A counterbalancing means for oven doors comprising a toggle having one arm pivoted eccentrically of the turning axis of the door and its other arm pivotally associated with the door frame, and means including a spring tending to straighten the toggle for all positions of the door.

8. A counterbalancing means for oven doors comprising a toggle having one arm pivoted eccentrically of the turning axis of the door and its other arm pivotally associated with the door frame, a second toggle formed in part by one of said arms and by an extension of the other arm, and a spring tending to flex said second toggle.

9. A counterbalancing means for oven doors comprising a toggle having one arm pivotally associated with the door frame and its other arm operatively connected with the door, and a spring acting upon said toggle whereby to restrain the movements of said toggle arms toward each other as the door is opened.

10. A counterbalancing means for oven doors comprising a toggle having one arm pivoted at one end to a stationary support and its other arm having a portion rigid therewith operatively connected with the door, and a spring connecting the free ends of said toggle arms tending to flex them whereby to restrain outward swinging movement of the doors, the arrangement being such that said rigid extension of one of the toggle arms forms with the other toggle arm a second toggle which is straightened as the first mentioned toggle is flexed.

11. A counterbalancing means for oven

doors comprising a pair of members one of which is pivoted to the oven door eccentrically of its turning axis and the other of which is pivoted at one end to the first mentioned member between the ends of the latter and its other end to a stationary support, and a spring acting upon the free end of the first member to swing it relative to the

second member, the arrangement being such that said second member constitutes one ¹⁰ arm of two toggles of which the other arms are formed by the first member.

In testimony whereof, I have hereunto affixed my signature.

GEORGE E. PICKUP.
